SLACK ADJUSTER

James W. Clark, Monmouth, Ill.

Continuation of application Serial No. 311,909, October 11, 1928. This application December 24, 1938, Serial No. 247,683. In Canada January 27, 1928

39 Claims. (Cl. 188—198)

This invention relates to slack adjusters for use with air brake equipment for railway cars, locomotives, tenders, urban and interurban cars and the like.

5 It is primarily an object of the invention to provide a slack adjuster which is operable through the instrumentality of the mechanism substantially as hereinafter described, which mechanism becomes active upon abnormal travel of the piston comprised in said equipment.

10 An important object of the invention is to maintain substantially uniform the travel of the aforesaid piston.

15 Another important object of the invention is to provide means operating under the influence of the push rod connected to said piston to take up automatically any slack which may occur as a result of wear upon the brake shoes or from any other cause which would effect the desired uniform piston travel.

20 A further important object of the invention is to provide an automatic slack adjuster, which will effectively perform its intended functions directly and simultaneously with the operation 25 of the brakes, thereby entirely preventing or greatly reducing what is known in the art as "undesired action."

25 The invention consists in the details of construction and in the combination and arrangement of the several parts of my improved slack adjuster whereby other objects and important advantages are attained and the device rendered simpler, less expensive and otherwise more convenient and advantageous for use as will be hereinafter set forth, or will become apparent during 30 the course of the following description.

35 In order that my invention may be better understood, I will now proceed to describe the same with reference to the accompanying drawings, 40 wherein:

Figure 1 is a diagrammatic view illustrating a slack adjuster constructed in accordance with an embodiment of my invention;

Figure 2 is a diagrammatic view illustrating a further embodiment of my invention;

Figure 3 is an enlarged detailed view in elevation illustrating the mounting of the capstan and certain of the parts associated therewith; and

Figure 4 is a horizontal sectional view taken substantially on the line 4—4 of Figure 3.

My improved slack adjuster may be employed in connection with the regular brake equipment without any material change in the rigging thereof.

55 As particularly illustrated in Figure 1, C de-

notes a brake cylinder in which operates a well known type of piston carrying the push rod 1. The rod 1 is operatively connected through the medium of a pin 2 with the live cylinder 3 which constitutes parts of all brake equipment.

5 The pin 2 also provides an operative connection between the rod 1 and an end portion of the operating lever 4, which constitutes an element of my improved slack adjuster. The rectilinear movement of the push rod 1 imparts swinging movement to the lever 4 as well as to the live cylinder lever 3, and for which reason said lever 4 is provided with a slot 5 through which the pin 2 is disposed in order to provide for such swinging movement. The slot 5 permits the lever 4 10 to move lengthwise at the connection afforded by the pin 2 allowing for a greater distance from the pin of the push rod to the center of the capstan or rotatable member A. The lever 4 15 has pivotal connection with the upper portion of a pin 6 which is supported by a capstan frame F. This frame F is bolted or otherwise affixed to a bracket B which in turn is bolted or otherwise effectively secured to the car sills.

20 Rotatably mounted upon the pin 6 is a capstan or rotatable member A provided with an upper flange 9 and a lower flange 10. The peripheral portion of the upper flange 9 is provided with a series of ratchet teeth 11 herein disclosed as fifteen in number and of duplicate form. The lower flange 10 is provided in its peripheral portion with the spaced ratchet teeth 12 and herein disclosed as ninety in number and of duplicate form.

25 Each of the teeth 11 is placed in vertical alignment with a point midway between two adjacent teeth 12, or may be placed in vertical alignment with one of the teeth 12.

30 The lever 4 has pivotally connected therewith, as at 14, a dog or pawl 15 which is constantly urged into contact with the flange 9 by means of the spring 16 having one end portion secured, as at 17, to the lever 4. Pivotally connected, as at 18, with the capstan frame F is a second pawl 19 which is constantly urged into contact with the flange 10 by means of the spring 20, also carried by the capstan frame F.

35 Winding on the capstan or rotatable member A between its flanges 9 and 10 is a cable or chain 21, one end of which is operatively connected, 40 as at 22, with the free end of a lever 23. The opposite end of the chain or cable 21 is suitably anchored, as at 24, to the capstan or rotatable member A so that upon rotation of said capstan under the influence of the pawl 15, a pull will 45

be exerted upon the outer or free end portion of the lever 23, or, in other words, the free end portion of the lever 23 will be moved toward the capstan.

5 The lever 23 is supported substantially midway its ends, as at 25, between the bars of the guide 26 and said lever 23, at 27, is operatively connected with the connecting rods 28 which in turn are also operatively connected, as at 29, with the 10 dead cylinder lever 30. It is to be noted that an extended end portion of the dead cylinder lever 30 has movement between the upper and lower bars of the guide 26 and is prevented from lengthwise movement by the pin 31 moving in the slot 15 32 provided in the guide bars 26. It is also to be noted that the fulcrum point 29 of the dead cylinder lever 30 is disposed upon the center line of the brake cylinder C.

The end portions of the bars of the guide 26 20 adjacent to the cylinder C are bolted, as at 33, to the cross bar 34 and the opposite end portions of the bars of the guide 26 are adapted to be bolted or otherwise suitably secured to a car sill. It is also to be noted that one end portion of the cross bar 34 of which the guide bars 26 are affixed is bolted, as at 35, to a cylinder bracket 36, while the opposite end portion of said cross bar 34 is bolted to a car sill or, if desired to an extended end portion of the capstan bracket B.

30 Connected with the lever 23 and with a suitably positioned bracket 37 is a retractile spring 38 of requisite tension to keep the dead cylinder lever 30 in its proper place and thus permit the brakes to be released. The dead cylinder lever 30 is operatively connected with the live cylinder lever 3 at points midway the ends of said levers by the tie rod 39.

As the rod 1 moves outwardly, swinging movement is imparted to the lever 4 and in the event that the outward movement of the rod 1, or piston travel, is for a distance greater than that for which the capstan A is set without operating, the pawl 15 engages the first tooth 11 on flange 9 and in the course of its movement will cause the 40 capstan or rotatable member A to be rotated a distance sufficient to permit the pawl 19 to engage the next tooth 12 on the lower flange 10 and to hold the capstan against retrograde rotation. When the brakes are released and the operating lever 4 moves backwards, the pawl 15 45 will engage the tooth 11 immediately succeeding the tooth with which it previously co-operated and when the brakes are again applied and the rod 1 moves outwardly, the capstan or member 50 A will be rotated a distance sufficient to bring the pawl 19 into cooperation with three of the teeth 12 on the lower flange 10 within the space separating the perpendicular alignments of the two teeth 11 on the operating or upper flange 9 55 between which the pawl 19 was brought into action in making such operation. The capstan or member A is held against retrograde movement by the pawl 19 which, as particularly illustrated in Figure 4, has its working and engageable with three of the teeth 12.

During this rotation of the capstan or member A just referred to, a pull will be exerted upon the chain or cable 21 resulting in moving the adjacent end portion of the dead cylinder lever 30 60 in a direction away from the cylinder C, and which movement in proper ratio is transmitted to the live cylinder lever 3. By this means the slack is taken out of the brake rigging and it will be 65 noted that the desired uniform travel of the brake

piston, or more particularly its rod 1, will be maintained.

Under normal conditions, or when the brake piston has the desired travel or less, it will be understood that the swinging movement of the operating lever 4 will have no effect upon the movement of the capstan A, as the pawl 15 only moves forward and backward in the space separating the two teeth 11 on the flange 9 between which the pawl 15 is moving. Upon further wear 10 of the brake shoes, brake rigging and wheels, the pawl 19, due to the influence of the pawl 15 acting upon a tooth 11 of the operating flange 9, coacting with the teeth 12 of the holding flange 10 will engage the succeeding intervening teeth 15 between the alignments hereinbefore referred to until the pawl 19 has engaged three teeth 12, the central one of which is either in perpendicular alignment or adjacent to a point that is in perpendicular alignment with the last succeeding 20 tooth 11 of the alignments hereinbefore referred to on the operating flange 9, then the slack adjuster upon additional wear of the parts above named will again operate as previously described and each succeeding operation takes place in 25 like manner.

For the purpose of explanation, a plurality of teeth 12 are to be considered in sections defined by the perpendicular alignments of the teeth 11. When the pawl 15 has engaged a succeeding tooth 30 11 and has operated the adjuster, the pawl 19 will engage teeth 12 of the following section, but the rotating member will not be rotated a distance sufficient to permit the pawl 19 to engage teeth 35 12 corresponding in position to the teeth of the section with which it formerly cooperated. This is due to the fact that the operation of the adjuster shortens the piston travel while said operation is being made. Again when the adjuster has taken up the slack as hereinbefore described 40 so that the central tooth of the pawl 19 has engaged tooth 12 either in perpendicular alignment or adjacent to a point that is in perpendicular alignment with a tooth 11, the central tooth of the pawl 19 must engage a tooth 12 beyond the 45 alignment just mentioned before the pawl 15 will engage the succeeding tooth 11 to again operate the adjuster. Because of the two foregoing reasons it is seen that the adjuster successively takes up slack by the pawl 19 engaging in succession several of the teeth 12 between the actions of the pawl 15 engaging successively two teeth 11. Also, it is seen that the slack taken 50 up by the major operation due to the pawl 15 engaging a tooth 11 is made less by the successive action of the pawl 19 engaging the teeth 12. 55

In the embodiment of my invention as illustrated in Figure 2, the cable or flexible member 21 coacts with the capstan A' in the same manner as referred to with respect to the cable 21, that is to say, resulting in a pull being exerted thereon as a result of abnormal travel of the push rod 1'. This member 21 is operatively engaged, as at 40, with the connecting rod 41 which in turn is operatively connected, as at 42, with an end portion of a lever 43.

Operatively connected with the lever 43 at a desired point intermediate its ends is a rod 44, which in turn is operatively connected as at 51 with a dead lever 45. The end portion of the lever 43 remote from the connecting rod 41 is operatively connected as at 55 through the medium of a tie rod 46 with a second lever 47 as at 56 herein disclosed as in converging relation with respect to the lever 43. This lever 47 has its end 75

portion remote from the tie rod 46 operatively connected as at 54 with a rod 48, which is suitably connected with a bracket 49 adapted to be secured to a car sill. The lever 47 is operatively connected through the medium of a tie rod 50 with the live cylinder lever 3'.

Upon rotation of the capstan A', a pull exerted upon the cable or member 21' results in a pull being imposed upon the rods 44 and 50 one toward the other. This action results in slack being taken out of the brake rigging, and thereby a substantially uniform brake piston travel is maintained. Connected with the lever 43 and with a suitably positioned bracket 51 is a retractile spring 52 of requisite tension, serving to maintain the levers 43 and 47 in their proper place and to overcome the inertia of said levers while the brakes are being released. Coacting with the opposite end portions of the levers 43 and 47 are the lever carriers 53 of a conventional type. The embodiment of the invention shown in Figure 2 tends to adjust the slack in the brake rigging in substantially the same manner as has been set forth in connection with the embodiment of the invention illustrated in Figure 1.

Hereinbefore the direct and simultaneous operation of the slack adjuster with the brake application has been described; but by turning the capstan upside down, changing the rack bar so that it comes into contact with the opposite side of the pinion from which side said bar is shown as contacting in the accompanying drawings, and changing the position of the pawls so that they engage their respective teeth in the proper manner, the slack adjuster can be caused to operate while the brakes are being released. Herewith arises the question of what is known as "undesired action", that is the operation of the slack adjuster upon the tilting of the truck levers caused by track conditions, the movements of the trucks and certain parts of the running gear. The operation of the slack adjuster due to such causes as listed above results in a brake piston travel much shorter than what is desired. This condition exists to a greater extent upon freight than passenger cars, due to the looser construction of the former. Yet, frequently the last named cars obtain too short a piston travel due to the aforesaid "undesired action" of an automatic slack adjuster resulting in damage thereto.

The direct and simultaneous operation of the slack adjuster with the brake application as fully described hereinbefore and as disclosed in the accompanying drawings acts as a causative agent to prevent the above described "undesired action". It is seen that when the brakes are applied, the piston moves forward, and if the piston's movement is abnormal as described, hereinbefore the pawl 15 comes into contact with a tooth 11, and no slight tilting of the truck levers, nor movements of parts of the running gear, nor trucks, can cause the aforesaid "undesired action" of the slack adjuster. This fact is apparent when it is understood that during such operation of both the brakes and the slack adjuster simultaneously the inertia of both the brake rigging and the slack adjuster is to be overcome, and the adjustment of parts of the rigging is to be accomplished, and the travel of the brake piston shortened synchronously with said simultaneous operations. With such a method of operation as immediately before described the slack adjuster will not operate until a positive, although slightly longer piston travel is obtained. It is

submitted that the slack adjusting mechanism hereinbefore described, particularly the structure of the holding flange possessing teeth entirely around said flange, disclosed as being relatively small in respect to the operating teeth, and arranged in succession one immediately adjacent to the other, is well adapted for the successful and practical operation of the slack adjuster simultaneously with the brake application.

Whereas if the operation of the slack adjuster were changed so that it operated as the brakes are being released, which method of operation is universally accepted as being the best, the causes being absent which prevent the aforesaid "undesired action" in the first explained method of operation, each slight tilting of the truck levers, or movement of the trucks or parts of the running gear toward the center of the car would cause the piston to move forward unduly carrying with it the piston rod, the operating arm, and the pawl thereon. These movements would permit said pawl to become engaged with the operating teeth so frequently that a too short a piston travel would result therefrom, resulting in the brake shoes not being removed from the wheels upon release of the brakes, giving too strong a braking power, and thereby causing slid flat wheels and broken equipment.

It is to be understood that the capstan A is to be set with respect to the center of travel of the pin 2 in accordance with the required uniform travel of the brake piston. Freight cars generally are supposed to have an eight inch running piston travel, passenger cars seven inch running travel, tenders six inch running travel, and locomotives four inch running travel. To compute the correct distance for the required piston travel, an isosceles triangle is constructed, the vertex of which is the center of pin 6 and the side lines are drawn through two adjacent teeth 11 on the operating flange 9. Add to the above triangle a triangle formed by drawing a line from the center of pin 6 through a point on the periphery of the holding flange 10 in perpendicular alignment with a tooth 11 on the operating flange 9. The other side of this triangle is a line drawn from the center of pin 6 through the next tooth 12 on the holding flange 10. Bisect the sum of these triangles; find the point at which the outer sides of the triangle, formed by the sum of the above specified angles, are eight inches apart on a line perpendicular to the bisecting line. The distance from the center of pin 6 to the point where the line drawn between the outer sides of the sum of the above specified triangles intersects the line which bisects the sum of the two angles is the correct distance to set the center of capstan A from the center of travel of pin 2 for an eight inch piston travel. In like manner the correct setting for seven, six and four inch piston travel can be computed.

No definite diameter is required for the flanges 9 and 10, although in practice from eight to twelve inches appear to be convenient sizes. The aforesaid flanges may be transposed to suit the convenience of installation.

It is to be understood that the number of teeth 11 and also the number of teeth 12 may be varied so long as each set of teeth has a definite relation with respect to the other set of teeth.

From the foregoing description it is thought to be obvious that a slack adjuster constructed in accordance with my invention is particularly well adapted for use by reason of the convenience and facility with which it may be assembled, installed

and operated manually when such operation is required; and it also will be obvious that my invention is susceptible to some changes and modifications in both structure and operation, such as 5 effecting the operation of the same upon release of the brakes, without departing from the principles and spirit thereof and for these reasons I do not wish to be understood as limiting myself to the precise arrangements and formations of 10 the several parts herein shown and described in carrying out my invention in practice except as hereinafter claimed.

This application is a continuation of application Serial No. 311,909, filed October 11, 1928, and 15 renewed April 11, 1935. Reference is also made to application Serial No. 207,858, filed May 13, 1933, which discloses and claims a specific embodiment of the invention covered by the broad claims of this application.

20 I claim:

1. In an air brake equipment, the combination with a push rod and a live cylinder lever operatively connected therewith, a mechanism, means for imposing movement upon said mechanism upon abnormal travel of said push rod, a second lever, said second lever being interposed in the brake rigging, means for holding said second lever for swinging movement, means for imposing the movement of said mechanism upon said second lever, a third lever, said third lever being interposed in the brake rigging, said third lever being supported at one end portion for swinging movement, means for operatively connecting the opposite end portion of the third lever to the second lever, an operative connection between the third lever and the live cylinder lever, the aforesaid movement imposed by said mechanism upon said second lever effecting movement of the third lever and the live cylinder lever to take 40 up slack in the brake rigging, and means coacting with the second lever to maintain the second and third levers in proper positions and to overcome the inertia of said levers while the brakes are being released.

45 2. In an air brake equipment, the combination with a push rod and a live cylinder lever operatively connected therewith, a mechanism, means for imposing movement upon said mechanism upon abnormal travel of said push rod, a second lever, said second lever being interposed in the brake rigging, the pivotal mounting for said second lever being intermediate the ends thereof, means for holding said second lever for swinging movement, means for imposing the movement of said mechanism upon said second lever, a third lever, said third lever being interposed in the brake rigging, said third lever being supported at one end portion for swinging movement, means for operatively connecting the opposite end portion of the third lever to the second lever, the pivotal mounting for said third lever being at the end portion thereof remote from the operative connection between the aforesaid second and third levers, an operative connection between the third lever and the said live cylinder lever, the aforesaid movement imposed by said mechanism upon said second lever effecting the movement of the third lever and the live cylinder lever to take up slack in the brake rigging.

70 3. The combination with a push rod, a dead lever of an air brake equipment, and a swinging lever operatively engaged with the rod; of means for operatively connecting said swinging lever to the dead lever including a rotatable member positioned to one side of the push rod and support-

ed independently thereof, a flexible member winding upon the rotatable member when rotated in one direction and exerting a pull upon the flexible member, a third lever, a guide for the dead cylinder lever positioned to contain the fulcrum 5 point for the third lever and to permit the operative connection between the dead cylinder lever and said third lever to be disposed upon the center line of the brake cylinder, means carried by the swinging lever operating upon undue travel 10 of the push rod and swinging lever for imparting rotation to said rotatable member, and means for holding the rotatable member against retrograde rotation, normal movement of the push rod operating the swinging lever independently 15 of the rotatable member.

4. A slack adjuster for a brake mechanism comprising a rotatable member provided with a plurality of circumferentially arranged elongated ratchet teeth, a dead lever comprised in the brake 20 rigging, an operative connection between said lever and the rotatable member, said connection including a transmission lever, a brake cylinder, a guide for the dead lever positioned and adapted to contain the pivot for the transmission lever 25 and to retain the operative connection between the dead lever and the transmission lever substantially upon the center line of the brake cylinder, a cross bar combined with the aforesaid guide, the transmission lever, the dead lever and 30 the brake cylinder whereby the forces exerted upon the opposite ends of said brake cylinder are substantially counterbalanced, a push rod of the brake equipment, an operating arm connecting said rod with the rotatable member, the pivotal mounting for said arm being in axial alignment with the rotatable member, a pawl carried by the arm and engageable with the ratchet teeth, said pawl normally coacting with a single tooth but engaging an adjacent tooth 40 upon abnormal functioning of the aforesaid rod, said rotatable member having a second series of teeth extending therearound, and a pawl engaging said second teeth for holding the rotatable member against retrograde movement, the 45 ratchet teeth of the first series being positioned substantially in vertical alignment with points definitely located and equi-distantly spaced amidst the ratchet teeth of the second series.

5. In an air brake equipment, the combination with a push rod and a live cylinder lever operatively connected therewith, a rotatable mechanism, an operating arm engaged with said push rod and rotatable mechanism, means carried by said operating arm to rotate the mechanism in one direction, means for preventing retrograde movement of said mechanism, a second lever operatively connected with said rotatable mechanism through the medium of a flexible member, means for holding the second lever for swinging 60 movement, the aforesaid rotatable mechanism, operating arm, and flexible member being adapted to exert a pull upon said second lever upon abnormal travel of the push rod, a third lever supported at one end portion for swinging movement, means for operatively connecting the opposite end portion of the third lever and the second lever, an operative connection between the third lever and the live cylinder lever, a dead lever, an operative connection between the dead 70 lever and the second lever, the movement imposed upon the second lever upon abnormal travel of the push rod effecting movement of the third lever, the dead lever, and the live cylinder lever to take up slack in the brake rigging.

6. In an air brake equipment, the combination with a push rod and a live cylinder lever operatively connected therewith, a rotatable mechanism, an operating arm engaged with said push rod and the rotatable mechanism, means carried by said operating arm to rotate the mechanism in one direction, means for preventing retrograde movement of said mechanism, a second lever operatively connected with said rotatable mechanism through the medium of a flexible member, means for holding the second lever for swinging movement, the aforesaid rotatable mechanism, operating arm, and flexible member being adapted to exert a pull upon said second lever upon abnormal travel of the push rod, a third lever supported at one end portion for swinging movement, means for operatively connecting the opposite end portion of the third lever and the second lever, an operative connection between the third lever and the live cylinder lever, a dead lever, an operative connection between the dead lever and the second lever, movement imposed upon the second lever upon abnormal travel of the push rod effecting movement of the third lever, the dead lever, and the live cylinder lever to take up slack in the brake rigging, the pivotal mounting for the second lever being intermediate the ends thereof, the abnormal travel of the push rod exerting a pull on one end of the second lever.

7. In an air brake equipment, the combination with a push rod and a live cylinder lever operatively connected therewith, a rotatable mechanism, an operating arm engaged with said push rod and the rotatable mechanism, means carried by said operating arm to rotate the mechanism in one direction, means for preventing retrograde movement of said mechanism, a second lever operatively connected with said rotatable mechanism through the medium of a flexible member, means for holding the second lever for swinging movement, the aforesaid rotatable mechanism, operating arm, and flexible member being adapted to exert a pull upon said second lever upon abnormal travel of the push rod, a third lever supported at one end portion for swinging movement, means for operatively connecting the opposite end portion of the third lever and the second lever, an operative connection between the third lever and the live cylinder lever, a dead lever, an operative connection between the dead lever and the second lever, movement imposed upon the second lever upon abnormal travel of the push rod effecting movement of the third lever, the dead lever, and the live cylinder lever to take up slack in the brake rigging, and a spring connected to said second lever and of a tension to maintain the second and third levers in proper positions and to overcome the inertia of said levers while the brakes are being released.

8. In an air brake equipment, the combination with a push rod and a live cylinder lever operatively connected therewith, a rotatable mechanism, an operating arm engaged with said push rod and the rotatable mechanism, means carried by said arm to rotate the mechanism in one direction, means for preventing retrograde movement of said mechanism, a second lever operatively connected with said rotatable mechanism through the medium of a flexible member, means for holding the second lever for swinging movement, the aforesaid rotatable mechanism, operating arm, and flexible member being adapted to exert a pull upon said second lever upon abnormal travel of the push rod, a third lever sup-

ported at one end portion for swinging movement, means for operatively connecting the opposite end portion of the third lever and the second lever, an operative connection between the third lever and the live cylinder lever, a dead lever, an operative connection between the dead lever and the second lever, movement imposed upon the second lever upon abnormal travel of the push rod effecting movement of the third lever, the dead lever, and the live cylinder lever to take up slack in the brake rigging, the pivotal mounting for the second lever being intermediate the ends thereof, the abnormal travel of the push rod exerting a pull on one end of the second lever.

9. In an air brake equipment, the combination with a push rod and a live cylinder lever operatively connected therewith, a rotatable mechanism, an operating arm engaged with said push rod and the rotatable mechanism, means carried by said operating arm to rotate the mechanism in one direction, means for preventing retrograde movement of said mechanism, a second lever operatively connected with said rotatable mechanism through the medium of a flexible member, means for holding the second lever for swinging movement, the aforesaid rotatable mechanism, operating arm, and flexible member being adapted for exerting a pull on said second lever upon abnormal travel of the push rod, a third lever supported at one end portion for swinging movement, means for operatively connecting the opposite end portion of the third lever and the second lever, an operative connection between the third lever and the live cylinder lever, a dead lever, an operative connection between the dead lever and the second lever, movement imposed upon the second lever upon abnormal travel of the push rod effecting movement of the third lever, the dead lever, and the live cylinder lever to take up slack in the brake rigging, the pivotal mounting for the second lever being intermediate the ends thereof, the abnormal travel of the push rod exerting a pull on one end of the second lever, the pivotal mounting for the third lever being at the end portion thereof remote from the operative connection between the second and third levers.

10. In combination with a dead cylinder lever and an operating member of an air brake equipment, a swinging lever having one end portion operatively engaged with said operating member and the other end thereof operatively engaged with a rotatable member, means for operating said swinging lever upon oscillation of the operating member of the equipment, means for operatively connecting the rotatable member with the dead cylinder lever through the medium of a flexible member and a third lever, a guide for the dead cylinder lever positioned to contain the fulcrum point for the third lever and to permit the operative connection between the dead cylinder lever and said third lever to be disposed upon the center line of the brake cylinder, normal movement of said operating member operating the swinging lever independently of the rotatable member, means operating upon undue travel of the operating member and swinging lever for imparting rotation to the rotatable member to move the third lever towards the said rotatable member and to take up slack in the brake rigging, and means for holding the rotatable member against retrograde movement.

11. A slack adjuster for a brake mechanism comprising a rotatable member provided with a plurality of circumferentially arranged elongated ratchet teeth, a dead lever comprised in the brake

- rigging, an operative connection between said lever and the rotatable member, said connection including a transmission lever, a brake cylinder, a guide for the dead lever positioned and adapted to contain the pivot for the transmission lever and to retain the operative connection between the dead lever and the transmission lever substantially upon the center line of the brake cylinder, a cross bar combined with the aforesaid guide, the transmission lever, the dead lever and the brake cylinder whereby the forces exerted upon the opposite ends of said brake cylinder are substantially counterbalanced, a push rod of the brake equipment, an operating arm connecting said push rod with the rotatable member, the pivotal mounting for said arm being in axial alignment with the rotatable member, a pawl carried by the arm and engageable with the ratchet teeth, said pawl normally coacting with a single tooth but engaging an adjacent tooth upon abnormal functioning of the push rod, said rotatable member having a second series of circumferentially arranged teeth, and a pawl engaging said teeth for holding the rotatable member against retrograde movement, a frame for rotatably supporting the rotatable member, the aforesaid arm being supported by said frame, and the second named pawl being pivotally mounted upon the frame.
12. In an air brake equipment, the combination with a push rod and a live cylinder lever operatively connected therewith, an operating mechanism, means for imposing movement upon said mechanism upon abnormal travel of said push rod, a second lever, said second lever being interposed in the brake rigging and operatively connected thereto, means for holding said second lever for swinging movement, means for imposing the movement of said mechanism upon said second lever, a third lever, said third lever being interposed in the brake rigging and supported at one end portion for swinging movement, means for operatively connecting the opposite end portion of the third lever to the second lever, an operative connection between the third lever and the live cylinder lever, the aforesaid movement imposed by said mechanism upon the second lever effecting the movement of the third lever and the live cylinder lever to take up slack in the brake rigging and to maintain a substantially uniform brake piston travel, and means coacting with the second lever to maintain the second and third levers in proper positions and to overcome the inertia of said levers while the brakes are being released.
13. In an air brake equipment, the combination with a push rod and a live cylinder lever operatively connected therewith, an operating mechanism, means for imposing movement upon said mechanism upon abnormal travel of said push rod, a second lever, said second lever being interposed in the brake rigging and operatively connected therewith, said second lever being adapted to operate as of both the first and the second class, means for holding the second lever for swinging movement, means for imposing the movement of said mechanism upon said second lever, a third lever, said third lever being interposed in the brake rigging and supported at one end portion for swinging movement, means for operatively connecting the opposite end portion of the third lever to the second lever, an operative connection between the third lever and the said live cylinder lever, the aforesaid movement imposed by said mechanism upon said second

lever effecting movement of the third lever and the live cylinder lever to take up slack in the brake rigging and to maintain a substantially uniform brake piston travel.

14. In an air brake equipment, the combination with a push rod and a live cylinder lever operatively connected therewith, a second lever, means for holding said second lever for swinging movement, means for imposing pull upon said second lever upon abnormal travel of the push rod, the last named means including an operating mechanism, a brake rigging, said second lever being operatively connected said brake rigging, a third lever supported at one end portion for swinging movement, means for operatively connecting the opposite end portion of the third lever to an end portion of the second lever, an operative connection between the third lever and the live cylinder lever, said means for imposing pull upon said second lever upon abnormal travel of the push rod effecting movement of the third lever and the live cylinder lever to take up slack in the brake rigging and to maintain a substantially uniform brake piston travel.

15. In an air brake equipment, the combination with a push rod and a live cylinder lever operatively connected therewith, a rotatable member, an operating arm connecting the push rod with said member, means carried by said arm to rotate the aforesaid member in one direction, means for preventing retrograde movement of the said member, a second lever operatively connected with the aforesaid member through the medium of a flexible element, means for holding the second lever for swinging movement, the aforesaid rotatable member, operating arm and flexible element being adapted to exert a pull upon said second lever upon abnormal travel of the push rod, a third lever supported at one end portion for swinging movement, an operative connection between the third lever and the second lever at an adjacent end portion of each, a dead lever, an operative connection between the dead lever and the second lever, the aforesaid movement imposed upon the second lever upon abnormal travel of the push rod effecting movement of the third lever, the dead lever, and live cylinder lever to take up slack in the brake rigging.

16. In an air brake equipment, the combination with a push rod and a live cylinder lever operatively connected therewith, a rotatable member, an operating arm connecting the push rod with said member, means carried by said arm to rotate the aforesaid member in one direction, means for preventing retrograde movement of the said member, a second lever operatively connected with aforesaid member through the medium of a flexible element, said second lever being adapted to operate as of both the first and the second class means for holding the second lever for swinging movement, the aforesaid rotatable member, operating arm and flexible element being adapted to exert a pull upon said second lever upon abnormal travel of the push rod, a third lever supported at one end portion for swinging movement, said third lever being adapted to operate as of the second class, an operative connection between the third lever and the second lever, an operative connection between the third lever and the live cylinder lever, a dead lever, an operative connection between the dead lever and the second lever at a point intermediate the ends of said second lever, the aforesaid movement imposed upon the second lever upon ab-

normal travel of the push rod effecting movement of the third lever, the dead lever, and the live cylinder lever to take up slack in the brake rigging.

5 17. In an air brake equipment, the combination with a push rod and a live cylinder lever operatively connected therewith, a rotatable member, an operating arm connecting the push rod with said member, means carried by said arm to rotate the aforesaid member in one direction, means for preventing retrograde movement of the said member, a second lever operatively connected with aforesaid member through the medium of a flexible element, said second lever being adapted 10 to operate as of both the first and the second class, means for holding the second lever for swinging movement, the aforesaid rotatable member, operating arm and flexible element being adapted for exerting a pull upon said second lever 15 upon abnormal travel of the push rod, a dead lever, an operative connection between the dead lever and the said second lever, an operative connection between the second lever and the said live cylinder lever, the aforesaid movement imposed upon the second lever upon abnormal travel 20 of the push rod effecting movement of the second lever and the live cylinder lever to take up slack in the brake rigging, and to maintain a substantially uniform brake piston travel.

20 18. In an air brake equipment, the combination with a push rod and a live cylinder lever operatively connected therewith, a rotatable member, an operating arm connecting the push rod with said member, means carried by said arm to rotate the aforesaid member in one direction, means for preventing retrograde movement of the said member, a second lever operatively connected with the aforesaid member through the medium of a flexible element, said second lever being 25 adapted to operate as of both the first and the second class, means for holding the second lever for swinging movement, the aforesaid rotatable member, operating arm and flexible element being adapted to exert a pull on said second lever 30 upon abnormal travel of the push rod, a brake rigging provided with an operative connection with the second lever at a point intermediate the ends of said second lever, an operative connection between the second lever and the live cylinder lever, the aforesaid movement imposed 35 upon the second lever upon abnormal travel of the push rod effecting movement of the second lever and the live cylinder lever to take up slack in the brake rigging, and to maintain a substantially uniform brake piston travel.

40 19. In combination with the elements of a brake rigging and a push rod, a slack adjuster for said brake rigging, said slack adjuster including levers interposed in the central portion 45 of the brake rigging and forming part of the means through which the braking force is applied by said push rod to the brake shoes, an operative connection between said levers, a mechanism operatively connected to said push rod, 50 an operative connection between said levers and said mechanism, means operating upon abnormal travel of said push rod effecting the movement of said mechanism, said levers being adapted to transmit the movement of said mechanism whereby slack is taken out of said rigging with substantially equal effectiveness in both end 55 portions thereof, and a substantially uniform brake piston travel is maintained.

55 20. In combination with a push rod, a live cylinder lever operatively connected thereto, a sec-

ond lever interposed in the central portion of a brake rigging, said second lever being adapted to operate as of both the first and the second class, a mechanism positioned to one side of the push rod and operatively connected thereto, an operative connection between the second lever and said mechanism, a dead lever, an operative connection between said dead lever and the aforesaid second lever, an operative connection between the said second lever and the aforesaid live cylinder lever, means operating upon abnormal travel of said push rod for operating said mechanism, the aforesaid second lever being adapted to transmit the operations of said mechanism with substantially equal effectiveness to both the live cylinder lever and the dead lever whereby slack is taken out of the brake rigging, and a substantially uniform brake piston travel is maintained.

21. The combination with a push rod, a live cylinder lever and a dead lever, a swinging lever operatively connected with the rod, means for operatively connecting said swinging lever with the dead lever, said means including a rotatable member positioned to one side of the push rod and supported independently thereof, a flexible member winding upon the rotatable member when rotated in one direction and exerting a pull upon the flexible member, a fourth lever operatively connecting the flexible member with the dead lever, a guide for the dead cylinder lever positioned to contain the fulcrum point for the fourth lever and to permit the operative connection between the dead cylinder lever and the fourth lever to be disposed upon the center line of the brake cylinder, means carried by the swinging lever operating upon undue travel of said push rod and swinging lever for imparting rotation to said rotatable member, and means for holding the rotatable member against retrograde rotation, normal movement of the push rod operating the swinging lever independently of the rotating member.

22. A slack adjuster for a brake mechanism comprising a rotatable member provided with a plurality of circumferentially disposed elongated ratchet teeth, a dead lever constituting an element of the brake rigging, an operative connection between said lever and said rotatable member, said connection including a transmission lever and a link connecting said transmission lever with said dead lever, a brake cylinder, a guide for said dead lever positioned and adapted to contain the pivot for the transmission lever, said link being positioned substantially upon the center line of the brake cylinder, the aforesaid guide, transmission lever, link, dead lever and brake cylinder being combined and adapted to counterbalance the forces exerted upon the opposite ends of said brake cylinder, a push rod of the brake equipment, an operating arm connecting said push rod with said rotatable member, a pawl carried by the arm and engageable with the ratchet teeth, said pawl normally coacting with a single tooth but engaging an adjacent tooth upon abnormal functioning of the push rod, said rotatable member having a second series of circumferentially disposed teeth, and a pawl engaging said second series of teeth for holding the rotatable member from retrograde movement, the teeth of the first series being positioned in vertical alignment with points definitely located and equidistantly spaced amidst the teeth of the second series.

23. In combination with a dead lever, a live

75

- cylinder lever, a push rod of a brake equipment, a rotatable member, a swinging lever having one end portion operatively connected to said push rod and the other end thereof operatively connected to the rotatable member, means to operate said swinging lever upon oscillation of said push rod, means for operatively connecting the rotatable member with said dead lever and said live cylinder lever, said means including a fourth lever, said fourth lever being adapted to transmit the movements of the rotatable member with substantially equal effectiveness to both said dead lever and said live cylinder lever, normal movement of said push rod operating the swinging lever independently of the rotatable member, means carried by said swinging lever to impart rotation to the rotatable member to move the fourth lever toward the said rotatable member upon abnormal travel of said push rod and said swinging lever, means for holding the rotatable member against retrograde movement, the last named means coacting with aforesaid means carried by said swinging lever whereby slack is successively taken out of the brake rigging.
24. A slack adjuster for a brake mechanism comprising a rotatable member provided with a plurality of circumferentially arranged elongated ratchet teeth, a dead lever, an operative connection between said lever and said rotatable member, said connection including a transmission lever, a brake cylinder, a guide combined with said dead lever and said transmission lever whereby the forces exerted upon the opposite ends of said brake cylinder are substantially counterbalanced, a push rod of the brake equipment, a pawl engageable with said ratchet teeth, said pawl normally coacting with a single tooth but engaging an adjacent tooth upon abnormal functioning of said push rod, said rotatable member having a second series of circumferentially arranged teeth, a pawl engaging said second series of teeth for holding the rotatable member against retrograde movement, the said second pawl and the second series of teeth being adapted to cooperate with the first named pawl and the first named series of teeth whereby slack is successively taken out of said rigging, a frame for rotatably supporting said rotatable member, an arm supported by said frame for swinging movement, the first named pawl being carried by said swinging arm, said arm operatively connecting the push rod with said rotatable member, the second named pawl being pivotally mounted upon the frame.
25. The combination with a push rod of a brake equipment, a dead lever thereof, a rotatable member, a transmission lever, a swinging lever, one end of said swinging lever being operatively connected with said push rod and the other end portion thereof being operatively connected with said rotatable member, a flexible element winding on said rotatable member and operatively connected to said transmission lever, said transmission lever being operatively connected to aforesaid dead lever, a guide adapted to serve as a brace for the brake cylinder, as a guide for the dead lever, a pivot for the transmission lever, and to retain the operative connection between the aforesaid transmission lever and said dead lever substantially upon the center line of the brake cylinder, means carried by said swinging lever and coacting with the rotatable member operating upon undue travel of said push rod and swinging lever for imparting rotation to said rotatable member, and means for holding the rotatable member against retrograde movement.
26. The combination with a push rod and a dead cylinder lever of a brake equipment, a swinging lever operatively connected with said push rod, an operative connection between said swinging lever and said dead cylinder lever, said connection including a rotatable member, a transmission lever and a flexible element to wind on said rotatable member, said swinging lever having swinging movement with respect to the axial center of the rotatable member, a guide for the dead cylinder lever, said guide being adapted to serve as a brace for the brake cylinder, a pivot for the transmission lever, and to retain the operative connection between the aforesaid transmission lever and said dead cylinder lever substantially upon the center line of the brake cylinder, the normal travel of said push rod operating the swinging lever independently of the rotatable member, means for imparting rotation to said rotatable member upon undue travel of said push rod to take up successively slack in the brake rigging, and means for holding the rotatable member against retrograde movement.
27. A mechanism to control the travel of the piston contained in an air brake cylinder, comprising a rotatable member provided with a plurality of circumferentially arranged elongated ratchet teeth, a member comprised in the brake rigging, an operative connection between said member and the rotatable member, a push rod of the brake equipment, an operating arm connecting said push rod with the rotatable member, a pawl carried by the arm and engageable with the ratchet teeth, said pawl normally coacting with a single tooth but engaging an adjacent tooth upon abnormal functioning of the push rod, said rotatable member having a second series of relatively small teeth extending therearound and arranged in succession one immediately adjacent to the other, said teeth being equidistantly spaced and with a plurality of said teeth within the perpendicular alignments of the first named teeth, a pawl engaging said second series of teeth for holding the rotatable member against retrograde movement, said second pawl and said second series of teeth being adapted to cooperate with said first pawl and said first series of teeth whereby said second pawl successively engages several of the teeth of said second series between the actions of said first pawl engaging successively two adjacent teeth of said first series, and with a definite number of teeth in each of the aforesaid series, said mechanism being adapted to determine the travel of the piston by the distance said rotatable member is set from the push rod.
28. A mechanism to control the travel of the piston contained in an air brake cylinder, comprising a rotatable member provided with a plurality of circumferentially arranged elongated ratchet teeth, a member comprised in the brake rigging and operatively connected with the rotatable member, a push rod of the brake equipment, an operating arm connecting said push rod with the rotatable member, a pawl carried by the arm and engageable with the ratchet teeth, said pawl normally coacting with a single tooth but engaging an adjacent tooth upon abnormal functioning of the push rod, said rotatable member having a second series of teeth extending therearound and arranged in succession one immediately adjacent to the other, said second series of teeth consisting of a multiple of said first series of teeth, a pawl engaging said second series

of teeth for holding the rotatable member against retrograde movement, said second pawl and said second series of teeth being adapted to cooperate with said first named pawl and said first series 5 of teeth whereby the said second pawl successively engages several of the teeth of the said second series between the actions of said first named pawl engaging successively two adjacent teeth of said first series, and with a definite number 10 of teeth in each of the aforesaid series, said mechanism being adapted to determine the travel of the piston by the distance said rotatable member is set from the push rod.

29. An adjuster to maintain a normal travel of 15 the piston contained in an air brake cylinder, comprising a rotatable member provided with a plurality of circumferentially arranged elongated ratchet teeth, a member comprised in the brake rigging and operatively connected with the rotatable member, a push rod of the brake equipment, means for operating the rotatable member upon abnormal movement of said push rod, said means including a pawl carried by an operating arm and engageable with said ratchet teeth, said rotating member having a second series of relatively small 25 teeth extending therearound and arranged in succession one immediately adjacent to the other, said teeth being equidistantly spaced and with a plurality of said teeth within the perpendicular alignments of said first series of teeth, a pawl 30 engaging said second series of teeth for holding the rotatable member against retrograde movement, said second pawl and said second series of teeth being adapted to cooperate with said first pawl and the first series of teeth whereby the said second 35 pawl successively engages several of the teeth of said second series between the actions of said first pawl engaging successively two adjacent teeth of said first series, means for supporting the afore- 40 said parts and members and controlling their movements, the operation and combinations of the above parts and members substantially as disclosed and specified.

30. An adjuster to maintain a normal travel of 45 the piston contained in an air brake cylinder, comprising a rotatable member provided with a plurality of circumferentially arranged elongated ratchet teeth, a member comprised in the brake rigging and operatively connected with the rotatable member, a push rod of the brake equipment, means for operating the rotatable member upon abnormal movement of said push rod, said means including a pawl carried by an operating arm and engageable with said ratchet teeth, said rotatable member having a second series of relatively small 50 teeth extending therearound and arranged in succession one immediately adjacent to the other, said teeth being equidistantly spaced and with a plurality of said teeth within the perpendicular alignments of the first named teeth, a pawl engaging said second 55 teeth for holding the rotatable member against retrograde movement, the first named pawl normally coacting with a single tooth of the first named series but engaging an adjacent tooth following the action of the second named pawl en- 60 gaging a succeeding number of the second series of teeth upon abnormal travel of the push rod, the said second pawl and the second series of teeth being adapted to cooperate with the first named pawl and the first series of teeth whereby the said 65 second pawl successively engages several of the teeth of the said second series between the actions of the first named pawl engaging successively two adjacent teeth of the first named series, with a definite number of teeth in each of the aforesaid 70 series, said mechanism being adapted to determine the travel of the piston by the distance said rotatable member is set from the push rod, the combination hereinabove set forth being adapted to operate simultaneously with the brake application, and thereby effecting a resistance to undesired action substantially as specified.

31. In a brake equipment, the combination with 75 a push rod, an operating mechanism, means for

imposing movement upon said mechanism upon abnormal travel of the aforesaid rod, a lever interposed in and operatively connected with the rigging of the said equipment, means for holding said lever for swinging movement, a second lever interposed in and operatively connected with said rigging, means for holding the second lever for swinging movement, an operative connection between the aforesaid levers, means for imposing the said movement imposed upon said mechanism upon the aforesaid levers whereby slack is taken out of the aforesaid rigging and a substantially uniform brake piston travel is maintained, and means acting to maintain the aforesaid levers in proper position and to overcome the inertia thereof while the brakes are being released.

32. In a brake equipment, the combination with a push rod, an operating mechanism, means for imposing movement upon said mechanism upon abnormal travel of said rod, a lever interposed in and operatively connected with the brake rigging of the aforesaid equipment, means for holding said lever for swinging movement, means for imposing the movement of said mechanism upon the aforesaid lever, a second lever interposed in and operatively connected with said rigging, means for holding said second lever for swinging movement, an operative connection between said levers, the aforesaid movement imposed by said mechanism upon the first named lever effecting the movement of the second named lever, the movements of said levers taking the slack out of the brake rigging and maintaining a substantially uniform brake piston travel.

33. A mechanism to control the travel of the piston contained in an air brake cylinder, comprising a rotatable member provided with a plurality of circumferentially arranged elongated ratchet teeth, a member comprised in the brake rigging and operatively connected with the rotatable member, a push rod of the brake equipment, an operating arm connecting said push rod with the rotatable member, a pawl carried by the arm and engageable with the ratchet teeth, said rotatable member having a second series of teeth extending therearound and arranged in succession one immediately adjacent to the other, said teeth being equidistantly spaced and with a plurality of said teeth within the perpendicular alignments of the first named teeth, a pawl engaging said second teeth for holding the rotatable member against retrograde movement, the first named pawl normally coacting with a single tooth of the first named series but engaging an adjacent tooth following the action of the second named pawl en- 55 gaging a succeeding number of the second series of teeth upon abnormal travel of the push rod, the said second pawl and the second series of teeth being adapted to cooperate with the first named pawl and the first series of teeth whereby the said second pawl successively engages several of the teeth of the said second series between the actions of the first named pawl engaging successively two adjacent teeth of the first named series, with a definite number of teeth in each of the aforesaid 60 series, said mechanism being adapted to determine the travel of the piston by the distance said rotatable member is set from the push rod, the combination hereinabove set forth being adapted to operate simultaneously with the brake application, and thereby effecting a resistance to undesired action substantially as specified.

34. A mechanism to control the travel of the piston contained in an air brake cylinder, comprising a rotatable member provided with a plu- 75

rality of circumferentially arranged elongated ratchet teeth, a member comprised in the brake rigging and operatively connected with the rotatable member, a push rod of the brake equipment, an operating arm connecting said push rod with the rotatable member, a pawl carried by the arm and engageable with the ratchet teeth, said rotatable member having a second series of relatively small teeth extending there-around and arranged in succession one immediately adjacent to the other, a pawl engaging said second teeth for holding the rotatable member against retrograde movement, the first named pawl normally coacting with a single tooth of the first named series but engaging an adjacent tooth following the action of the second named pawl engaging a succeeding number of the second series of teeth upon abnormal travel of the push rod, with a definite number of teeth in each of the aforesaid series, said mechanism being adapted to determine the travel of the piston by the distance said rotatable member is set from the push rod, the combination hereinabove set forth being adapted to operate simultaneously with the brake application and thereby effecting a resistance to undesired action substantially as specified.

35. An adjuster to maintain a normal travel of the piston contained in an air brake cylinder, comprising a rotatable member provided with a plurality of circumferentially arranged ratchet teeth, a member comprised in the brake rigging and operatively connected with the rotatable member, a push rod of the brake equipment, means for operating the rotatable member upon abnormal travel of the push rod, said means including a pawl carried by an operating lever and engageable with the ratchet teeth, said rotatable member having a second series of teeth extending there-around, a pawl engaging the said second teeth for holding the rotatable member against retrograde movement, the first named pawl normally coacting with a single tooth of the first named series but engaging an adjacent tooth following the action of the second named pawl engaging a succeeding number of the second series of teeth upon abnormal travel of the push rod, the combination hereinabove set forth being adapted to operate simultaneously with the brake application and thereby effecting a resistance to undesired action substantially as specified.

36. In combination with the elements of a brake rigging and a push rod, a slack adjuster for said rigging, said slack adjuster including an operating mechanism, a lever operatively connecting said push rod with said operating mechanism, means carried by said lever to actuate said operating mechanism upon abnormal travel of said push rod, and a single transmission between said operating mechanism and an element in the central portion of said rigging, said transmission including a lever provided at its mid-portion with an operative connection with said element of said rigging substantially in the central portion thereof, said recited elements of the slack adjuster constituting means

to take up slack in said rigging simultaneously with the brake application and thereby to effect a resistance to undesired action substantially as described.

37. In combination with the elements of a 5 brake rigging, said elements including a live cylinder lever, a dead lever and an operative connection between said levers, a brake cylinder, a push rod, a slack adjuster for said rigging, said slack adjuster including an operating mechanism, a lever operatively connecting said push rod with said operating mechanism, means carried by said connecting lever to actuate said operating mechanism upon abnormal travel of 10 said push rod, and a single transmission between 15 said operating mechanism and said dead lever, said transmission including a lever provided at its mid-portion with an operative connection with said dead lever in proximity to said brake cylinder, said recited elements of the slack adjuster 20 constituting means to take up slack in said rigging simultaneously with the application of the brakes and thereby to effect a resistance to undesired action substantially as described.

38. In combination with the brake cylinder 25 and push rod of a brake equipment and the elements of a brake rigging, said brake rigging being adapted to be operated by said push rod, a slack adjuster for said rigging, said slack adjuster including an operating mechanism, means 30 operatively connecting said push rod with said operating mechanism, means operatively associated with said connecting means to actuate said operating mechanism upon abnormal travel of said push rod, and an operative connection 35 between said operating mechanism and an element comprised in said rigging, said operative connection including a transmission lever provided at its mid-portion with an operative connection with said element of said rigging in proximity to said brake cylinder, said recited elements of the slack adjuster 40 constituting means to take up slack in said rigging simultaneously with the brake application and thereby to effect a resistance to undesired action substantially as 45 described.

39. In combination with the brake cylinder and push rod of a brake equipment and the elements of a brake rigging, said brake rigging being adapted to be operated by said push rod, a slack adjuster for said rigging, said slack adjuster including an operating mechanism, means 50 operatively connecting said push rod with said operating mechanism, means operatively associated with said connecting means to actuate said operating mechanism upon abnormal travel of said push rod, an operative connection between 55 said operating mechanism and an element in the central portion of said rigging, and operative connections from said last named element to both ends of said brake rigging, said recited elements of the slack adjuster constituting means 60 to take up slack in said rigging simultaneously with the brake application and thereby to effect a resistance to undesired action substantially as 65 described.

JAMES W. CLARK.
